STOKER

Paul A. Ketchpel, Bergenfield, N. J., assignor to
The Standard Stoker Company, Incorporated,
a corporation of Delaware

Application September 15, 1937, Serial No. 163,929

4 Claims. (Cl. 110—105.5)

The present invention relates to stokers employing a fluid stream for propelling fuel through a conduit and into the furnace for distribution over the grates thereof.

One object of this invention resides in the provision of a novel stoker of the type specified and wherein the fluid stream utilized to propel fuel through the conduit and into the furnace is heated prior to its admission over the firebed.

Another object of this invention is to provide means for propelling fuel through the conduit by an air stream having a relatively short passage from its point of generation to the point of discharge into the stoker conduit.

A further object of this invention resides in the provision of improved means for operating the fan utilized to generate the air stream in the stoker conduit, and whereby a very compact relation is attained between the stoker conduit, the fan and drive unit for said fan.

A still further object of this invention resides in providing new and improved means for heating the air which is utilized to propel fuel through the conduit and into the furnace.

Other objects, together with their advantages, will become apparent as the following description of the invention is read in connection with the accompanying drawings, in which:

Figure 1 is a central vertical longitudinal section through the rearward portion of a locomotive and adjacent portion of its tender, showing the invention in side elevation as applied thereto, portions of which are in section;

Figure 2 is an elevation of the structure shown in Figure 1 as viewed along the line 2—2 of Figure 1;

Figure 3 is a plan view taken on the line 3—3 of Figure 1 with portions of the locomotive in section and other portions removed;

Figure 4 is a sectional view taken on the line 4—4 of Figure 2;

Figure 5 is a sectional view taken on the line 5—5 of Figure 4;

Figure 6 is a sectional view taken on the line 6—6 of Figure 4;

Figure 7 is a sectional view taken substantially on the line 7—7 of Figure 4; and

Figure 8 is a sectional view taken on the line 8—8 of Figure 1.

On the drawings, the locomotive L is provided with a frame 10 above which is supported a boiler firebox or furnace 11 having grates 12, and a backwall 13. The backwall 13 is provided with an opening 14 above the grates 12 and cab deck

15. Rearward of the locomotive L is a tender T having a frame 16 and a deck 17.

Fuel stored on the tender is conveyed and distributed over the firebed by means of a stoker S which includes a tubular conduit 18 leading forwardly from the tender T to a fuel discharge or delivery conduit 19 mounted on the locomotive L. The conduit 18 comprises a pair of telescoped sections 20, 21, the latter having a spherical shell 22 fitted within the spherical seat 23 formed at the lower end of the discharge conduit 19, forming a universal connection 24 between the conduits 18 and 19. A conveyor screw 25 is disposed within the conduit 18 and urges fuel forwardly into the lower portion of the discharge or delivery conduit 19, the latter being provided with a ledge 26 extending forwardly and upwardly from the spherical seat 23 to form a lip 27 over which fuel urged by the conveyor screw 25 falls downwardly toward a chamber 28 disposed subjacent the ledge 26.

The fuel delivered into the conduit 19 is propelled therethrough and distributed over the firebed by a swiftly moving stream of air. For generating the air stream through the conduit 19, a fan 29 is provided and it is disposed within a housing 30 formed at one side of the discharge conduit 19. The fan 29, which is driven through a shaft 30 disposed forward of the lip 27 and below the bottom wall 31 of the conduit 19, is provided with an axial air intake opening 32 formed in the cover 33 of the housing 30, and a radial outlet 34 arranged to communicate through a duct 35 with the chamber 28. It will be observed that the outlet 34 is at one side of the conduit 19, but that the duct 35 curves inwardly toward the chamber 28 whereby the swiftly moving stream of air will be discharged axially into the conduit 19 through an aperture 36 formed between the ledge 26 and the lower end of the bottom wall 31. Foreign matter in the fuel too heavy to be propelled by the air stream will lodge in the chamber 28 from which it may be removed through openings 9 upon detachment of the covers 8.

On the side of the conduit 19 opposite the fan 29 is a turbine 37, the wheel 38 of which is secured in known manner to the fan shaft 30. The turbine wheel 38 is enclosed within a casing 39 formed at one side of the conduit 19 and includes a cover 40 which carries the steam intake and exhaust pipes 41, 42 for supplying steam to the turbine 37 and for exhausting it therefrom, respectively. The turbine operates at a speed sufficiently high which will enable the air stream

generated by the fan 29 to lift the larger fuel particles or lumps for propulsion into the firebox 11. Preferably, the fuel fed by the conveyor screw 25 to the conduit 19 is first reduced, by well-known means, to a size which can be efficiently propelled and distributed by an air stream.

Air is supplied to the axial intake opening 32 of the fan 29 by means of a curved tubular elbow 43, one end of which is secured to the fan housing cover 33 and the opposite end of which is attached to the expansion plate 44, the latter forming a support for the rearward end of the boiler firebox 11 and also defines the rearward extent of a chamber 45 with which the tubular elbow 43 communicates. The back sheet 46 of the ash pan 47 defines the forward extent of the chamber 45 which is closed on its bottom by a plate 48 and a door 49 arranged to be opened or closed manually through linkage 50. The ash pan sheet 46 is perforated at 51 for withdrawal of air from the ash pan 47 into the fan intake elbow 43. Preferably, the chamber 45 is provided with a baffle 52 which causes air entrained from the ash pan 47 to pass through spaces between the pipes 53 which contain steam or other heating medium. In this manner, the air entering the fan 29 is relatively warm whereby it will have no detrimental effect upon firebox conditions when admitted thereto by the fan. In fact, the warm air entering the firebox will promote combustion by thoroughly mixing with unburned particles of fuel and in this manner supply the oxygen necessary for their complete combustion. The air which enters the ash pan 47 along the sides 54 of the firebox 11 may also be heated by providing heating pipes 55, as shown in Figure 8. Any ash particles which may be entrained through the perforations 51 into the chamber 45 will settle in the trough 56 formed by the converging plate 48 and door 49. By entraining the air around the baffle 52, its course, and that of any fuel or ash particles carried thereby, is changed considerably so that the solid particles will drop for accumulation in the trough 56. At intervals, the door 49 may be opened to allow the accumulated ash particles to escape from the trough 56.

At its forward end, the discharge conduit 19 is secured by bolts 57a to a frame 58 which embraces the firing opening 14 and is secured to the firebox backwall by bolts 57 and also carries a door 59 to close that portion of the firing opening above the terminal end 60 of the stoker conduit. The lower end of the conduit 19 is provided with a flanged foot member 61 which rests upon a guideway 62 formed with the locomotive frame 10. The terminal end 60 of the conduit 19 includes a hood portion 63 which is detachably secured to the conduit 19 and the frame 58 by bolts 64 and 65, respectively. Upon opening of the firedoor 59 and removal of bolts 64, 65, the hood portion 63 may be removed to afford free and easy access into the firebox.

Upon being propelled through the conduit 19 by the air stream, the fuel is caused to be deflected evenly to all parts of the firebed by means of distributor D. In effect, the distributor D stops the forward advance of certain portions of the fuel stream and causes such portions to be deflected to predetermined areas of the firebed. This distributor D consists of a lower deflector member 66 and an upper deflector 67, the latter including a pair of independently operable sections 67a and 67b. The lower deflector 66 is secured by bolts 68 to the stoker conduit 75

19 and fits between the wall-like extensions 69, 70 formed with the firedoor frame 58, which extensions are disposed within the firing opening 14. A V-shaped block 71 is formed on the upper surface of the lower deflector 66 and serves to spread laterally portions of the lower stratum of fuel as it is propelled through the conduit 19.

The sections 67a, 67b of the upper deflector 67 are carried by the hood portion 63 whereby they may be removed from their position in the firing opening 14 upon detachment of the hood portion 63 from the stoker conduit 19. On its central forward portion, the hood portion 63 is provided with a lug 72 in which is journalled a pin 73 which also has secured thereto the deflector section 67b. The outer end of the pin 73 is journalled in the hood portion 63 and carries a handle 74 whereby the deflector section 67b may be raised or lowered about the axis of pin 73. The deflector section 67a is provided with a pin 75 and is also supported on its inner end upon the pin 73. A handle 76 affords manual angular adjustment of the deflector section 67a about the axis of the pins 73, 75, independent of the adjustment of deflector section 67b. Each handle 74, 76, is provided with a latch 77 arranged to engage any one of a number of holes 78 formed in the hood portion 63 adjacent a respective handle whereby each deflector section 67a, 67b may be securely locked in its adjusted position. Each deflector section 67a, 67b is provided on its underside with an outwardly curved rib 81, 82, respectively, for deflecting laterally portions of the upper stratum of fuel propelled through the conduit 19.

From the foregoing, it will be apparent that a novel stoker has been provided which employs a heated air stream for propelling fuel through the stoker and over the firebed; the construction being such that distribution of projected coal may be controlled at one side of the firebed independently of the opposite side. Furthermore, a novel arrangement has been attained between the fan, its driving turbine and the stoker discharge conduit; the arrangement being of a compact design so as to occupy very little space and at the same time, the fan discharges an air stream into the discharge conduit by a duct having a very direct communication between the discharge conduit and the outlet of the fan. In this manner, the stated objects of this invention have been fully attained.

I claim:

1. In a furnace having a grate and an ash compartment therebeneath, a stoker for supplying fuel over said grate comprising a discharge conduit leading from a source of fuel and communicating with said furnace, means for generating an air stream in said conduit for propelling fuel toward the furnace, means providing a passage for supplying air from said ash compartment to said first named means, and a heating device in said passage intermediate said ash compartment and said first named means for heating the air passing from said ash compartment to said first named means.

2. In a furnace having a grate, and an ash compartment therebeneath arranged to receive air, a stoker for supplying fuel over the grate comprising a discharge conduit leading from a source of fuel and communicating with said furnace, means for generating an air stream in said conduit for propelling fuel toward the furnace, a chamber adjacent said ash compartment and in communication therewith, a conduit estab-

lishing communication between said chamber and said first named means, said first named means arranged to entrain air from said ash compartment to said chamber and from said chamber to said last named conduit, means in said chamber for separating ash particles from the entrained air stream, and a heating device in said chamber for warming the air passing therethrough into said second named conduit.

3. In combination, a firebox having a grate 10 and an ash compartment therebeneath, means for preheating the air for combustion in the firebox including walls forming a chamber adjacent said ash compartment, one of said walls having apertures for admission of hot air from the ash compartment to said chamber and the opposite wall being provided with an outlet, a plate within 15 said chamber separating said air admission apertures from said outlet and forming a baffle, said baffle forming with said chamber walls a 20 circuitous passage within said chamber, heating elements disposed in said circuitous passage, and means communicating with said outlet for with-

drawing air from said ash compartment through said chamber and outlet and arranged to introduce it into said firebox.

4. In combination, a firebox having a grate 5 and an ash compartment therebeneath, means for preheating the air for combustion in the firebox including walls forming a chamber adjacent said ash compartment, said walls including a perforated wall common to said chamber and ash compartment providing communication therebetween, and a wall opposite said perforated wall having an outlet, a plate within said chamber separating said perforated wall from said outlet and forming a baffle, said baffle forming with said chamber walls a circuitous passage within said chamber, heating elements disposed in said circuitous passage between said baffle and said second named wall, and means communicating with said chamber for withdrawing air from said ash compartment through said perforated wall, chamber and outlet and arranged to introduce it into said firebox.

PAUL A. KETCHPEL.
